UNITED STATES PATENT OFFICE.

WALTER J. SOTH, OF HONOLULU, TERRITORY OF HAWAII.

FASTENER.

Application filed October 20, 1923. Serial No. 669,762.

To all whom it may concern:

Be it known that I, WALTER J. SOTH, a citizen of the United States, residing at Honolulu, in the Territory of Hawaii, have invented certain new and useful Improvements in Fasteners, of which the following is a specification.

This invention relates to improvements in fasteners and particularly to that type of fastener employed in the securing of collars to the neckbands of shirts.

The main object of this invention is to provide a fastener for the above purpose wherein the liability of the usual extension tongues of the collar as well as the back portion thereof becoming detached from the neckband of the shirt is reduced to a minimum.

An additional object is the provision of such a fastener that is of such a shape whereby should the same drop upon the floor it will not tend to roll about and become lost as is now the case with the usual collar button employed for this purpose.

An additional object is to provide such an article wherein the same may be manufactured and marketed at a cost extremely less than the cost of the manufacture and marketing of the above mentioned collar button.

With the above and other objects in view as the nature of this invention is better understood, the same comprises the novel form of the invention as set forth in the following specification, shown in the accompanying drawing and claimed.

In the drawing, wherein there is shown the most practical embodiment of my invention and wherein like reference characters indicate corresponding parts throughout the several views.

Figure 1 is a perspective view partly broken away, of a collar shown as being attached to the neckband of a shirt through the medium of a pair of my novel fasteners.

Figure 2 is a front elevational view of this fastener, and

Figure 3 is an edge view thereof.

With specific reference to the drawing, my novel fastener embodies a relatively V-shaped piece of sheet metal 5 the corners of which are relatively long and are inturned for providing clasps 6, the portions of the material forming these clasps being bent inwardly adjacent their outer ends and then

outwardly at 7 whereby the same may be engaged through the buttonholes provided in the collar as well as in the neckband of the shirt as hereinafter set forth.

In Figure 1 the collar designated 8 has its usual end tongue portions formed at their upper edges and at opposite sides of the usual longitudinal buttonholes at their lower edges with vertical buttonholes as shown. The back of the collar is also provided above the usual longitudinal button-hole and at opposite sides thereof with vertical buttonholes for obviously receiving the uppermost clasp members 6 of my improved fastener.

In actual practice, and after the lowermost clasp elements of a pair of these fasteners are engaged through the buttonholes at the front and rear of the neckband 9 of a shirt 10 the buttonholes at the rear of the collar 8 receive the clasps 6 of the rearmost fastener after which the collar may be engaged around the neck and the buttonholes of the end tongue members manifestly also receiving the clasp members 6 of the foremost fastener for thereby practically absolutely preventing the unfastening of the collar 8 from the neckband of the shirt.

In view of the above it will at once be apparent that I have provided a highly novel and simplified form of fastener whereby collars may be securely attached to the neckbands of shirts and wherein the liability of the same becoming disengaged therefrom is reduced to a minimum.

Minor changes may be made within the invention without departing from the spirit and scope of the appended claim.

Having thus described my invention, what I claim as new and desire to secure by Letters Patent is:—

A collar fastener comprising a triangular plate having at the apices of its angles, in-turned hook portions disposed over the intermediate portion of the plate, the median longitudinal dimensions of two of the hooks 100 at adjacent corners of the plate being substantially in longitudinal alinement with each other and the median longitudinal dimension of the remaining hook portions being disposed in alinement with the center of 105 the plate.

In testimony whereof I affix my signature.
WALTER J. SOTH.
